(57) **CLAIM**

The ornamental design for a flow control apparatus, as shown and described.

DESCRIPTION

FIG. 1 is a side perspective view of a flow control apparatus in accordance with our design, as viewed from a top front corner thereof;

FIG. 2 is a front elevation view thereof;

FIG. 3 is a rear elevation view thereof;

FIG. 4 is a bottom plan view thereof;

FIG. 5 is a top plan view thereof;

FIG. 6 is a right side elevation view thereof; and,

FIG. 7 is a left side elevation view thereof.

The broken lines shown in the figures depict environmental subject matter and form no part of the claimed design.

1 Claim, 5 Drawing Sheets
